UNITED STATES PATENT OFFICE.

KARL VÖLLER, OF DUSSELDORF, GERMANY.

MOUNTING GUN-CARRIAGE SPADES.

1,108,032.

Specification of Letters Patent. Patented Aug. 18, 1914.

Application filed August 2, 1913. Serial No. 782,667.

To all whom it may concern:

Be it known that I, KARL VÖLLER, engineer, a subject of the German Emperor, residing at 12 Scharnhorststrasse, Dusseldorf, 5 Germany, have invented certain new and useful Improvements in the Mounting of Gun-Carriage Spades; and I do hereby declare the following to be a full, clear, and exact description of the invention, such as 10 will enable others skilled in the art to which it appertains to make and use the same.

The invention relates to wheeled gun carriages and more particularly to the mounting of spades, which can be put in and out 15 of action as required, and in which a pressure plate is hinged to the spade and prevents the spade from penetrating too deeply into the ground. In previously known constructions of spades with hinged pressure 20 plates several operations are required to put the spade in and out of action and the manipulation in consequence is too complicated.

According to the present invention the operations of putting the spade in and out of gear are very much simplified by the arrangement in which the pressure plate is hinged to the spade, so that when the spade 25 is moved the pressure plate is also moved.

A construction according to the invention 30 is shown in the drawing, in which—

Figure 1 is a side view of the device in the working position, Fig. 2 is a side view in the position, in which the pressure plate is automatically released from the limber eye when 35 the spade is put out of action. Fig. 3 is a plan view from above.

The spade *a* is hinged to the gun carriage *b* about the pin *c* so that in the working position it can be turned down, until it rests against the fixed spade *d*, and on the other hand can be turned over for the purpose of putting it out of action, so as to lie on the end of the trail in the position shown by the chain dotted lines in Fig. 1. A 40 pressure plate *f* is hinged by pins *e* to the spade *a*, and has on the under side a hook *g*, which can engage with the end of the limber eye *h*.

In the out of action position, the spade *a* 45 and the pressure plate *f* lie on the rear end of the trail as shown by the chain dotted lines in Fig. 1 and are held in this position

in transport by the lug *i* of the hand spike *k* which has been turned forward.

The lug *i* presses against the blade of the 55 spade in the dotted position and prevents both the spade *a* and the pressure plate from rising. If the gun is to be fired with only the fixed spade *d* in use, the spade *a* and the pressure plate *f* are held in the dotted positions by the projection on the hand spike. 60

The spade *a* and pressure plate *f* are changed over into the working positions by turning the hand spike *k* out of the transport position in the direction shown by the 65 arrow until the projection *i* releases the spade *a*. The spade *a* is then turned over until it rests against the fixed spade *d* when a pin *l* carried by the spade *a* snaps into a catch *m*, and locks the spade in its position. 70 The hook *g* of the pressure plate engages the limber eye as the spade *a* is turned over against the spade *d*, fixing the pressure plate in its position.

The change from the working position is 75 effected by releasing the catch *m* by a handle *n* and then turning back the spade *a*. The pressure plate *f* is thereby turned back so far to the right (Fig. 2), that the hook *g* is released from the limber eye *h*, whereupon 80 the spade and pressure plate are turned together into the position shown dotted in Fig. 1.

I claim as my invention:

1. A wheeled gun carriage having a spade 85 capable of being moved into and out of operative position, and a pressure plate hinged to said spade and movable therewith.

2. In combination with the trail of a wheeled gun carriage, a spade capable of 90 being moved into and out of operative position, a pressure plate hinged to said spade and movable therewith, and a locking member on said pressure plate designed to engage the eye of said trail to hold said spade 95 and plate in operative position.

3. In combination with the trail of a wheeled gun carriage, a spade capable of being moved into and out of operative position, a pressure plate hinged to said spade 100 and movable therewith, a catch for holding said spade in operative position, and means on said trail for holding said pressure plate and spade in an inoperative position.

4. In combination with the trail of a wheeled gun carriage, a spade capable of being moved into and out of operative position, a pressure plate hinged to said spade and movable therewith, a movable element for holding said spade and pressure plate out of operation, and a hand spike for controlling said element.

In testimony whereof, I have signed this specification in the presence of two sub- 10 scribing witnesses.

KARL VÖLLER. [L. s.]
